Patented Aug. 13, 1918

UNITED STATES PATENT OFFICE.

CHARLES D. SMITH, OF DAYTON, OHIO, ASSIGNOR TO THE FIRM OF MORNER AND SMITH, OF DAYTON, OHIO, A COPARTNERSHIP CONSISTING OF LOUIS MORNER AND CHARLES D. SMITH.

CARBURETER.

1,275,620.

Specification of Letters Patent. Patented Aug. 13, 1918.

Application filed July 3, 1916. Serial No. 107,239.

To all whom it may concern:

Be it known that I, CHARLES D. SMITH, a citizen of the United States, residing at Dayton, in the county of Montgomery and State of Ohio, have invented certain new and useful Improvements in Carbureters, of which the following is a specification, reference being had therein to the accompanying drawing.

10 This invention relates to carbureters and is designed more particularly for use in connection with automobile engines, although its use is not limited to such engines. Much difficulty has been experienced in providing 15 a carbureter which will furnish a mixture of the proper richness in the proper quantities at all speeds of the engine. Where the carbureter is set to provide a proper mixture for low speeds, an increase in the 20 speed of the engine causes a larger proportion of gasoline to be drawn through the nozzle, thus producing a richer mixture. It has been proposed to overcome this difficulty by providing a supplemental air opening which will be controlled by a valve 25 which will open only when the speed of the engine becomes such as to tend to enrich the mixture delivered by the main feeding device. This supplemental device may feed 30 air alone, to reduce the suction on the main feeding device as well as to dilute the mixture, or it may also feed an additional quantity of gasoline for the higher speeds. These supplemental feeding devices have not been 35 entirely satisfactory however, because of the failure of the valve to act regularly at all speeds and consequently the failure of the supplemental devices to produce a uniform mixture. Various attempts have been made 40 to secure a regular movement of the valve, the most common device being the dash-pot, but while these devices have improved the operation of the supplemental feeding device they have not entirely overcome the 45 difficulty and are open to various objections.

The object of the present invention is to provide a carbureter with a supplemental feeding device which will be regular in its action and will deliver a uniform mixture 50 to the engine at all speeds.

To this end it is a further object of the invention to provide a suction operated air valve with means for causing a regular movement thereof at all speed conditions.

It is also an object of the invention to 55 combine with such an air valve a supplemental valve controlled gasoline nozzle which will be controlled by the movement of the air valve.

It is also an object of the invention to 60 provide a device of this kind which will be very simple in its construction and its operation and which can be easily kept clean and in an efficient operating condition, and which can be manufactured at a low cost.

It is also an object of the invention to 65 provide improved means for mounting the valve which controls the flow of gasoline to the carbureter.

In the accompanying drawings Figure 1 70 is a vertical sectional view taken centrally through a carbureter embodying my invention; Fig. 2 is a sectional view taken on the line $x-x$ of Fig. 1; Fig. 3 is a sectional view taken on the line $y-y$ of Fig. 1; 75 Fig. 4 is a perspective detail view of the air valve and the controlling means therefor; and Fig. 5 is a perspective detail view of the main gasoline nozzle.

In these drawings I have illustrated one 80 embodiment of my invention and have shown the same as applied to a carbureter of a well known type, the main features of construction of which form no part of the present invention except in so far as they 85 may enter into combination with the features which I have added to the carbureter. The particular carbureter here shown is of that type known as the concentric float type and utilizes a heated air supply, but it will 90 be understood that the invention is applicable to carbureters of various kinds and that the present embodiment of the invention is shown for the purpose of illustration only, and it will be also understood that the term "gasoline" is herein used as indicating any suitable fuel with which the carbureter will operate, the carbureter here shown being designed for gasoline.

The carbureter here shown comprises a 100 casing 1 adapted to be secured to an explosive engine and having an inferior passageway 2 adapted to communicate with the intake of the engine. When used with the ordinary automobile engine the device is 105 usually mounted so that the passageway will communicate with the intake manifold. Arranged in this passageway is the usual thrott-

tle valve or "butterfly", 3. Secured to the casing 1, beneath the passageway 2, is a gasoline receptacle, here shown in the form of a bowl 4, having a laterally extending conduit 5 provided with a nipple 6, by means of which it may be connected with a suitable source of gasoline supply. The gasoline may be fed to the receptacle by gravity, air pressure, or in any suitable manner, and the flow of gasoline to the receptacle is controlled by the level of the gasoline therein. To this end a float 7 is mounted in the bowl 4 and connected with one end of a lever 8 which is pivotally mounted in the conduit 5 and carries at its outer end a valve 9 which controls the port connecting the nipple 6 with the conduit. This valve is so mounted on the lever 8 as to have free swinging movement to enable it to accommodate itself to the movement of the lever. In order to provide this free movement of the valve and to render the same adjustable, I have threaded into the end of the lever 8 a stud 10 having a substantially spherical socket 11 in which is mounted a ball 12 carrying the valve 9. After the ball has been seated in the socket, the edges of the socket are drawn about the same to so reduce the opening as to permanently retain the ball within the socket, thus providing a very strong connection between the valve and its supporting device and one which will at all times permit of a free swinging movement of the valve.

35 The gasoline is fed from the receptacle 4 to the passageway 2 by causing a current of air to pass about the end of a nozzle which communicates with the gasoline receptacle, in the well known manner. As here shown, 40 a tube 13, such as is commonly known as a choke tube, is screw-threaded into an opening in the casing 1 and is in open communication with the passageway 2. The lower end of the tube 13 is mounted in an opening 45 in the bottom of the gasoline receptacle 4 and is in open communication with a suitable source of air supply. This source of air supply may be of any suitable kind, such as open communication with the atmosphere, 50 but the present carbureter is designed for use with a heated air supply and to this end an air conduit 14 is secured to the carbureter in open communication with the air tube 13 and leads to a suitable air heater. The choke 55 tube has the usual restricted portion between its ends and is flared toward the passageway 2. Extending through the restricted portion of the tube and into the flared discharge mouth thereof is a nozzle 15 which is carried 60 by a spider, or cross arm, 16, mounted in the lower end of the tube 1 and which communicates by means of a conduit 17 with the interior of the gasoline receptacle. Thus the suction created in the passageway 2 by the operation of the engine will draw a supply

of air through the choke tube and past the end of the nozzle 15 thereby causing gasoline to be drawn from the receptacle 4 through the nozzle and to be mixed with the air in the passageway 2. The nozzle, or jet, 70 is controlled by a needle valve 18. In the present construction, in order to more thoroughly break up the gasoline, I have provided the nozzle with a relatively wide but very thin discharge opening, so that the gasoline will be discharged in a thin flat spray. The nozzle is provided with a seat for the needle valve 18, at a point near its point of connection with the cross arm 16. This valve is mounted in an extension 19 projecting downwardly from the cross bar 16 and having an interior opening screw-threaded to receive the screw-threaded stem of the needle valve, this stem extending beyond the end of the extension 19 and having a handle 80 20 by means of which the valve may be manipulated. The extension 19 extends through a projection beyond the air conduit 14 and has its exterior surface screw-threaded to receive a nut 21 by means of 90 which the several parts of the carbureter are clamped together. It will be noted that the float 7 is ring-shaped in construction and is arranged concentrically of the air tube.

95 The main features of the carbureter as so far described are well known in the art and when the nozzle is adjusted for low speeds, the increased suction created by high speeds of the engine will, as heretofore explained, result in the production of too rich a mixture. I have therefore provided a supplemental feeding device which may feed either air alone or which may feed both air and gasoline. To this end I have provided an additional air-opening leading to the passageway 2. In the present construction the casing 1 is provided with a lateral extension 22 having therein a chamber which is in open communication with the passageway 2 and is provided at its outer end with an air-opening. This air-opening is controlled by a valve arranged to be opened by the suction created in the passageway 2, when this suction exceeds a certain predetermined point. As here shown the valve, which is 100 shown at 23, is mounted within the chamber in the extension 22 of the casing 1 and has an annular portion provided with a flat exterior surface to engage a valve seat formed by the inner edge of a ring 24 which is 110 screw-threaded into the outer end of the casing and has a head 25 by means of which it may be adjusted. The valve 23 is provided with surfaces converging along the line of movement of the valve toward its 115 open position, that is, toward the passageway 2. Preferably these surfaces are formed by providing the valve with a cone-shaped portion 26, which is here shown as formed integral with the annular seat en- 120 125 130

gaging portion thereof. This cone shaped portion of the valve preferably terminates in a cylindrical portion 27 which is tubular in construction, for purposes which will herein-
 5 after appear. Co-operating with the valve to hold the same normally in engagement with its seat and to offer progressively increasing resistance to the movement of the same toward its fully open position is a resilient de-
 10 vice comprising a plurality of parts, such as the resilient fingers 28, arranged to bear against the converging surfaces of the valves and to be spread apart by these surfaces as the valve moves toward the passageway 2.
 15 The resilient devices, or fingers, 28, may be mounted in any suitable manner and may be of any suitable number, but as here shown there are three resilient fingers and they are mounted at their inner ends in a collar, or ring, 29, which is mounted in the extension 22 of the casing and set against a shoulder formed at the inner end thereof. This construction enables the fingers to converge sharply toward the smaller portion of the cone 26 and to bear against the same in such a manner as to hold the valve firmly on its seat. The free ends of the resilient arms are preferably curved to form a smooth sliding contact with the cone. While I prefer to
 20 form the cone on the valve and to mount the resilient engaging devices within the casing, this is not essential to the operation of the device, as a reversal or other re-arrangement of the positions might be made and more or less satisfactory results secured. It will be
 25 apparent that the valve will be held normally on its seat and that when the suction within the passageway 2 becomes so great as to overcome the resistance of the spring fingers, the valve will open and as the suction increases the valve will be moved farther and farther away from its seat, thus increasing the size of the air opening, but as the suction increases and the valve moves
 30 farther and farther from its seat, the resistance offered to the movement becomes greater and greater. Hence it moves uniformly and regularly with changes of speed of the engine after the suction becomes great enough
 35 to unseat it.

In the present device I have provided means for feeding a supplemental supply of gasoline to the passageway at high speeds of the engine. To accomplish this I have
 40 provided a supplemental nozzle or feeding tube 30 which is here shown as arranged substantially centrally of the chamber in the extension 22 and mounted in a socket 31 secured to and preferably formed integral with the ring, or collar, 29, which carries the resilient devices 28. This nozzle has a lateral opening by means of which it communicates with a conduit 33 formed in the arm 32 and communicating with a tube 34
 45 which enters the conduit 33 and extends into the gasoline receptacle 4. The nozzle 30 is valve controlled and to this end it is provided with a flaring end 35 which forms a valve seat to receive a valve member 36 which is reversely tapered and is provided
 50 with a stem 37 which extends through a reduced opening 38 at the outer end of the valve seat and serves to guide the valve in its movement toward and away from its seat. The nozzle, or tube, 30, is provided
 55 at a point beyond the reduced opening 38 with an enlarged opening extending lengthwise thereof, through which the valve stem 37 extends and within which is coiled a spring 39 which bears at one end against a shoulder formed at the inner end of the opening in the tube, at the other end against a head 40 carried by the stem 37. The outer end of the nozzle, or tube, 30, is open so that the head 40 of the valve stem is exposed and may be engaged to actuate the valve. This actuation of the valve is preferably accomplished by the movement of the air valve 23, and to this end the hollow cylindrical portion 27 of the air valve has
 60 been shaped to fit about the tube 30 with a sliding fit and the outer end of this cylindrical portion of the valve has been provided with a boss 41 into which is screw-threaded a stud 42 having its inner end projecting into the hollow cylindrical portion of the air valve and adapted to enter the open end of the nozzle, or tube, 30, and engage the head of the valve stem 37. This screw-threaded stud is provided at its outer end
 65 with a knurled head 43 by means of which it may be adjusted and a spring 44 bears against the same to offer frictional resistance to its movement and thus prevent an accidental disturbance of its adjustment. It will be apparent that as the air valve 23 moves toward its fully open position the stud 42 will engage the stem of the gasoline valve 36 and open the nozzle to an extent corresponding to the air opening, thus permitting the gasoline to be drawn through the nozzle into the passageway 2. The connection between the air valve and the valve controlled nozzle may be so adjusted that the gasoline nozzle will be opened at the first movement of the air valve away from its seat or it may be so adjusted that the nozzle will not be opened until the air valve has moved a distance sufficient to provide an air opening of a predetermined size.
 70 The timing of the opening of the nozzle with relation to the movement of the air valve is secured by adjusting the screw-threaded stud 42. In addition to this adjustment the speed, or suction, at which the air valve will open may be adjusted by altering the position of the collar 24 which forms a seat for the air valve. This collar may be secured in its adjusted position in any suitable manner, but preferably, I split the outer

end of the extension 22 of the casing and provide the same with lugs 45 through which extends a clamping screw 46 which serves to draw the split end of the casing tightly about the collar and secure the latter firmly into position.

The operation of the device will be readily understood from the foregoing description and it will be apparent that I have provided means for automatically feeding a supplemental supply of air or of air and gasolene to the engine which will be controlled by the speed at which the engine is operated and which will be of such a character that the movement of the controlling valve will be regular and uniform with changes of speed thus furnishing a proper quantity of air and enabling a mixture of a proper richness to be maintained at all speeds.

Further it will be apparent that the device is very simple in its construction; that it has no complicated adjustments or delicate parts which are liable to be broken or disarranged or to become clogged by dirt or corrosion.

While I have shown and described one embodiment of my invention I wish it to be understood that I do not desire to be limited to the details of construction as obvious modifications will occur to a person skilled in the art. For example, the lateral extension to the casing is here shown as of a length great enough to inclose the air valve, the gasolene nozzle, and the coöperating devices. Obviously these devices need not all be mounted in the extension, and, particularly when the air valve is used without the supplemental gasolene nozzle, the extension may be shortened until it projects little, if any, beyond the side of the main casing, it being only necessary that a valve seat should be provided with which the air valve may coöperate. The resilient fingers and guides may be mounted on the casing in any suitable manner.

Having now fully described my invention, what I claim as new, and wish to secure by Letters Patent, is:

50. 1. In a carbureter having a passageway leading to the intake of an engine and having an air opening communicating with said passageway, a valve to control said air opening, said valve being arranged to be opened by the suction in said passageway and having surfaces converging in the direction of its opening movement, and resilient fingers acting on said surfaces to resist the movement of said valve toward its fully open position.

60. 2. In a carbureter having an air opening provided with a valve seat, a valve normally in engagement with said seat and having surfaces converging away from said seat, and a plurality of resilient fingers converging to-

ward the inner portion of said valve and having their inner ends arranged to normally engage the converging surfaces of said valve and to ride over the same as said valve moves away from its seat.

3. In a carbureter, a casing having a passageway leading to the intake of an engine and communicating with a main source of air and fuel supply, and also having a supplemental air opening extending laterally from said passageway and communicating therewith, an inwardly opening valve to control said supplemental air opening, said valve having converging surfaces extending transversely to said passageway, and resilient fingers carried by said casing and extending transversely to said passageway to engage said converging surfaces of said valve and resist the movement of said valve toward its open position.

4. In a carbureter, a casing having a laterally extending portion having its outer end open and provided with a valve seat, a valve mounted in said extension to engage said valve seat and having surfaces converging away from said valve seat, a collar mounted in said casing at a point remote from said valve seat, and resilient devices carried by said collar and arranged to engage the converging surfaces of said valve to resist the movement of the latter away from its seat.

5. In a carbureter, a casing having a laterally extending portion having its outer end open and provided with a valve seat, a valve mounted in said extension to engage said valve seat and having surfaces converging away from said valve seat, a collar mounted in said casing at a point remote from said valve seat, and a series of resilient fingers rigidly secured to said collar and spaced about the same, said fingers converging toward said valve and having their inner ends curved to provide sliding contact with the converging surfaces of said valve member.

6. In a carbureter, a casing having a laterally extending opening and having a valve seat surrounding said opening, an inwardly opening valve in said casing to engage said valve seat, said valve having a cone-shaped portion extending away from the valve seat, a supporting structure mounted in said casing in alignment with said opening, and resilient devices carried by said structure to engage the cone-shaped portion of said valve to resist its inward movement, said supporting structure and said valve having parts coöperating to guide the valve in its movement toward and from its seat.

7. In a carbureter comprising a casing provided with an extension open at one end and having a valve seat surrounding said opening, a valve mounted in said extension to engage said valve seat, said valve having a cone-shaped portion extending away from

- 5 said valve seat and also having an opening arranged at the apex of said cone, a collar mounted at a point remote from said valve seat and a part carried by said collar to enter the opening in said cone and form a guide therefor, and resilient devices mounted on said collar and arranged to engage said cone to resist the movement of said valve away from said seat.

10 6. In a device of the character described, a casing having a lateral extension, open at its outer end and provided with a valve seat adjacent to said outer end, an inwardly opening valve movable lengthwise of said extension to engage said seat and control the passage of air through said extension, a gasoline nozzle mounted at the inner end of said extension in line with said air opening, a valve to control said nozzle, an operative connection between said valves, and resilient devices mounted on said casing near the inner end of said extension and arranged to resist the inward movement of said first-mentioned valve.

15 7. In a device of the character described, a casing having a lateral extension open at one end and provided with a valve seat, a valve mounted in the extension of said casing and having surfaces converging away from said valve seat, a collar mounted at a point remote from said valve seat, resilient devices carried by said collar to engage the converging surfaces of said valve, a supplemental gasoline nozzle carried by said collar, a valve to control said nozzle, and means carried by said air valve to actuate the last-mentioned valve to open said gasoline nozzle.

20 8. In a device of the character described, a casing having a lateral extension open at one end and provided with a valve seat, a valve having an annular portion to engage said valve seat and having a hollow cylindrical portion connected with said annular portion by converging surfaces, a collar mounted at a point remote from said valve seat, resilient devices carried by said collar and engaging said converging surfaces to resist the movement of said valve away from its seat, a supplemental gasoline nozzle carried by said collar and having a portion extending into the hollow cylindrical portion of said valve to form a guide for the latter, a spring actuated valve to control said gasoline nozzle having a stem, and a part carried by said air valve to engage said stem and actuate said last-mentioned valve to open said nozzle.

25 9. In a device of the character described, a casing having a lateral extension open at one end and provided with a valve seat, a valve having an annular portion to engage said valve seat and having a hollow cylindrical portion connected with said annular portion by converging surfaces, a collar mounted at a point remote from said valve seat, resilient devices carried by said collar and engaging said converging surfaces to resist the movement of said valve away from its seat, a supplemental gasoline nozzle carried by said collar and having a portion extending into the hollow cylindrical portion of said valve to form a guide for the latter, a spring actuated valve to control said gasoline nozzle having a stem, and a part carried by said air valve to engage said stem and actuate said last-mentioned valve to open said nozzle.

30 10. In a device of the character described, a casing having a lateral extension open at one end and provided with a valve seat, a valve having an annular portion to engage said valve seat and having a hollow cylindrical portion connected with said annular portion by converging surfaces, a collar mounted at a point remote from said valve seat, resilient devices carried by said collar and engaging said converging surfaces to resist the movement of said valve away from its seat, a supplemental gasoline nozzle carried by said collar and having a portion extending into the hollow cylindrical portion of said valve to form a guide for the latter, a spring actuated valve to control said gasoline nozzle having a stem, and a part carried by said air valve to engage said stem and actuate said last-mentioned valve to open said nozzle.

35 11. In a device of the character described, a casing having a lateral extension open at one end and provided with a valve seat, a valve having an annular portion to engage said valve seat and having a hollow cylindrical portion connected with said annular portion by converging surfaces, a collar mounted at a point remote from said valve seat, resilient devices carried by said collar and engaging said converging surfaces to resist the movement of said valve away from its seat, a supplemental gasoline nozzle carried by said collar and having a portion extending into the hollow cylindrical portion of said valve to form a guide for the latter, a spring actuated valve to control said gasoline nozzle having a stem, and a part carried by said air valve to engage said stem and actuate said last-mentioned valve to open said nozzle.

40 12. In a device of the character described, a casing having a lateral extension open at one end and provided with a valve seat surrounding said opening, a valve having an annular portion to engage said valve seat, and a cone shaped portion terminating in a hollow cylindrical portion at its inner end, a collar mounted at a point remote from said valve seat, resilient devices carried by said collar to engage the cone shaped portion of said valve to resist its movement from its seat, said collar having a radial arm, a supplemental gasoline nozzle supported by said arm and having a part extending into the hollow portion of said valve to form a guide for the latter, a valve to control said gasoline nozzle having a stem for actuating the same, a spring acting on said stem to hold said valve normally seated, and a stud adjustably mounted on said air valve and arranged to engage said stem to actuate said last-mentioned valve to open said gasoline nozzle as said air valve moves away from its seat.

45 13. In a device of the character described, a casing having a lateral extension open at one end and provided with a valve seat surrounding said opening, a valve arranged to engage said valve seat, a supplemental valve controlled, gasoline nozzle, a structure mounted within said extension to support said nozzle, an operative connection between said nozzle and said air valve to cause the nozzle to be opened as said air valve moves away from its seat, said air valve and said supporting structure having co-operating parts to control the movement of said valve, said parts comprising a cone carried by one of said members and resilient devices carried by the other of said members and arranged to engage said cone to resist the movement of said air valve.

50 14. In a device of the character described, a casing having an extension at one end and provided with a valve seat, a valve to engage said seat, a supplemental gasoline nozzle, a supporting structure mounted in said extension and having an arm to support said nozzle, said arm having a conduit leading to a source of gasoline supply, said supporting structure and said air valve having co-operating parts to resist the movement of said air valve.

55 15. In a device of the character described, a casing having an extension at one end and provided with a valve seat, a valve to engage said seat, a supplemental gasoline nozzle, a supporting structure mounted in said extension and having an arm to support said nozzle, said arm having a conduit leading to a source of gasoline supply, said supporting structure and said air valve having co-operating parts to resist the movement of said air valve.

valve, said parts comprising a cone secured to one end of said members and resilient fingers secured to the other of said members and arranged to engage said cone as said 5 valve moves away from its seat.

15. In a carbureter, a supplemental feeding device comprising an air valve having surfaces converging in the direction of its movement toward its open position, and re- 10 silient fingers converging toward said valve and having their ends arranged to engage the converging surfaces of said valve to resist its movement toward its fully open position.

15 16. In a device of the character described, a casing having a laterally extending opening and provided with a valve seat surrounding said opening, a valve arranged to engage said valve seat, a supple-

mental valve-controlled gasoline nozzle, 20 a structure mounted within said casing to support said nozzle in axial alinement with said opening, an operative connection between the valve of said nozzle and said air valve to cause the nozzle to be opened as 25 said air valve moves away from said seat, said air valve and said supporting structure having coöperating parts to control the movements of said air valve, said parts comprising a cone carried by one of said members, and resilient devices carried by the other of said members, and arranged to engage said cone to resist the movement of said air valve.

In testimony whereof I affix my signature 35 hereto.

CHAS. D. SMITH.
